UNITED STATES PATENT OFFICE.

GUSTAVE F. SCHMIDT, OF CHICAGO, ILLINOIS.

GAS-REGULATING DEVICE.

Application filed October 22, 1923. Serial No. 669,939.

My invention relates to a device for regulating the flow of gas and more especially for controlling the supply or flow of the gas to the burners of a gas heater or gas stove, 5 without offering restrictions to the proper flow.

The invention has for its object the provision of a device which may be readily applied to a gas cock direct or to any type of 10 gas cock as at present employed by the use of a connecting member or nipple.

Another object of my invention is to provide a device whereby regulation or control of the gas flow may be obtained without necessitating any change or interfering in any 15 way with the air control of the burner; the device being easily adjustable without the use of special tools and enabling regulation or adjustment to a nicety, while the general 20 cross-sectional shape or contour of the issuing gas-stream for normal uses may be maintained to provide stability and velocity to the gas stream so as to induce entrainment of the requisite amount of air.

25 A further object of the invention is to provide a device which will be comparatively cheap to manufacture; composed of few parts and therefore easy to assemble and simple in adjustment.

30 The above enumerated objects and advantages as well as other advantages inherent in the construction will all be more fully comprehended from the detailed description of the drawing, wherein:—

35 Figure 1 is a side elevation of my invention applied to a gas-cock or well known type of shut-off valve, in conjunction with a portion of the mixing chamber or burner.

Figure 2 is an enlarged longitudinal sectional view, taken substantially on the line 40 2—2 of Figure 1.

Figure 3 is a longitudinal sectional view of a modified form of the gas controlling tube or pin.

45 Figure 4 is a similar view showing a modified manner of attachment.

Figure 5 is a perspective view of a modified form of the gas-controlling tube or pin shown in Figure 2.

50 Figure 6 is a perspective view of the gas controlling tube or pin shown in Figure 3.

Figure 7 is a sectional perspective view of a modified form of the coupling or attachment shown in Figure 4.

55 My invention relates to a device for regulating the flow of gas to a burner and at the

same time to discharge the gas in definite form whereby a straight stream or jet is obtained having the desired velocity; the device being more especially applicable to gas 50 burning heating devices or stoves. The application of my device to a burner of the type usually employed in gas heating ovens or stoves is disclosed in Figures 1 and 2, wherein a portion of supply pipe or line is 55 shown at 15 to which a well known type of cock or key valve is secured at 16. Where the body of the valve 16 at its outlet end is provided with an externally threaded nipple 17 and the outlet provided with the internal 70 shoulder as at 18, see Figure 2, my improved gas regulator may be secured directly to the valve 16.

The regulator comprises a short hollow pin or small tubular member 19 which is 75 adapted to abut against the shoulder 18; the pin or tubular member being provided with one or more longitudinal slots disposed transversely therethrough and extending to the delivery end of the pin or member 19, 80 as shown at 20 in Fig. 2. The bore of the pin or member 19 may either taper toward the delivery end or be reduced in diameter at a short distance from the delivery end as by means of the inwardly projecting lips 85 or portions 21 as shown in Figure 2. The pin or tubular member is intended to be of sufficiently resilient metal, such as brass, with the walls preferably of comparative thickness, in order that the slit end or the 90 segmental portions may be compressed or brought into closer relation with each other than normally is the case, or into abutting relation, upon proper manipulation of the controlling member 22 and also to return to 95 normal position as soon as the controlling member 22 is turned in the opposite direction.

The pin or tubular member 19 is provided with a smooth outer surface so as to be free 100 to slide in the member 22 and the outer or discharge end of the member 19 is beveled or tapered as shown at 23 which conforms to the taper or bevel on the interior of member 22, as shown at 24.

105 The controlling member 22 is in the nature of a sleeve adapted to have more or less snug sliding fit with the pin or tubular member 19; while the inner end of the controlling member 22 is shown preferably enlarged 110 and provided with wrench-receiving or grasping surfaces as at 25 in Figure 1; while

the inner surface of the enlarged portion of the sleeve is threaded to screw onto the threaded nipple 17 of the valve member 16. The threaded end of controlling member 22 is made slightly longer than the threaded nipple in order that the controlling member 22 may be screwed onto the nipple a distance sufficient to cause the outer end of the sleeve or member 22 to completely compress the 10 slotted or slit end of the pin or tubular member 19 through which the gas is conveyed.

In Figures 1 and 2 I show my invention applied to a well known type of mixing chamber 26 in advance of the burner proper; 15 the flared inlet end of the mixing chamber being usually provided with a transverse web or portion 27 which in turn is provided with a threaded nipple 28 to receive the air-controlling disc 29 which is adapted to screw 20 lengthwise of the nipple 28 so as to control the size of the air opening into mixing chamber 26. In the construction shown in Figure 2 the controlling member or sleeve 22 is shown with a smooth external surface 25 so as to have a sliding fit with the threaded nipple 28, thereby enabling quick and easy assembling of the parts.

In Figure 3 I show a modified form of the controlling device, wherein the pin or tubular member 30 is provided with a single slot 31 disposed transversely through the walls of the member, thus dividing the discharge end of the member into two segmental slightly separated portions; while the bore of the 30 member 30, like that in Figure 2 is shown reduced at the delivery end thereof by means of the lips or inwardly projecting portions 32, 32 similar to those shown at 21 in Figure 2. With this construction, like that shown 35 in Figure 2, a complete contraction of the segmental end portions of the pin or tubular member will result in a circular opening or discharge outlet for the gas; while on the other hand a separation of the segmental 40 portions will cause the gas issuing from the device to be discharged with a central cylindrical portion having four radiating wing portions, when the device shown in Figure 2 is employed or a cylindrical portion having 45 two radiating wing portions when the device shown in Figure 3 is used. The construction shown in Figure 3 also differs from that shown in Figure 2 in that the controlling member or sleeve 33 is provided with 50 a threaded end 34 adapted to screw into the inlet end or mixing chamber of a burner; while the enlarged faceted end of the controlling member 33 is internally threaded to screw onto the threaded nipple of the body 55 of the valve 16 similar to that shown in Figure 2.

In Figure 4 I show a further modification of the invention in that the device involves a coupling member or connecting nipple 35 having the intermediate wrench-receiving

surfaces 36 and the two threaded ends; the one end being adapted to screw into the body of a valve as at 37; while the other end is provided with an internal shoulder 38 against which the pin or tubular member 19 70 abuts. This last mentioned end of the coupler or connecting nipple 35 is threaded to receive the controlling member or sleeve 33, which, like sleeve member 22 has its outer end provided with an internal bevel or tapered surface as at 24 to correspond with the beveled surface at the outer end of the pin or tubular member 19. As is apparent from the construction shown, inward movement of the pin 19 is prevented by the 80 shoulder 38 of the coupling or connecting nipple 35, so that when the controlling member or sleeve 33 is screwed onto the coupler or connecting nipple 35, the beveled surface 24 of the controlling member will force the 85 slightly separated segmental portions at the discharge end of the pin or tubular member 19 into closer relation with each other than normally is the case; the proximity of the segmental portions to each other being determined by the extent to which the controlling member or sleeve 33 is screwed onto the coupler or connecting nipple 35. On the other hand, the unscrewing of the controlling member or sleeve 33 will permit the outer 90 end of the pin or tubular member 19 to return to normal position due to the resiliency of the metal.

Instead of providing the coupler or connecting nipple 35 with an internal shoulder 100 38, it may be of the construction shown in Figure 7 where the connecting nipple 39 is externally similar to that shown at 35 in Figure 4, while the bore is tapered toward one end as shown at 40. With this construction, the pin or tubular member 19 is inserted in the enlarged end of the bore and the extent of its insertion controlled by the taper of the bore in member 39 so that further inward movement of the pin or tubular 105 member, when the controlling member 33 is screwed onto the coupler or connecting nipple, will be prevented.

In Figure 6 the tubular member or pin employed in Figure 3 is shown in perspective, namely a pin provided with a single transverse slit or slot 31 and with a small central opening or port as at 41, like that shown in Figure 3, so that when the separated segmental portions of the tube are 115 brought into abutting relation at the outer ends, a small circular jet will be provided to permit a minimum discharge of gas sufficient to maintain combustion; whereas in Figure 5 I show, in perspective, a pin or tubular member 42 provided with the intersecting slits or slots 43, arranged similar to slots 20 in Figure 2 except that the inturned ends or lips 44 are not formed to provide the central discharge port or opening as at 41 in Figure 120 125 130 135 140 145 150 155 160 165 170 175 180

6. With the construction shown in Figure 5, it is apparent that when the controlling member or sleeve is screwed inwardly either on the threaded nipple of the valve 16, or 5 the coupler or connecting nipple 35 or 39 as the case may be, the separated segmental portions of the pin or tubular member 42 will be brought into complete abutting relation at the outer ends and thereby 10 completely shut off the flow of gas through said pin or member, thus in reality constituting a valve whereby the discharge of gas may be controlled; this construction therefore 15 constituting a gas valve as well as a flow regulating device.

My invention, as disclosed in the drawing, provides a regulating device consisting of few parts; a device which is adapted to be connected to the usual or well known type of 20 gas-valve or cock and a construction which permits of regulation of the gas flow to a nicety by reason of the minute degree of adjustment obtainable through the threaded connection of the controlling member or sleeve 25 with the threaded nipple. At the same time, my improved device causes the gas stream to be discharged with a definite cross-sectional configuration whereby the necessary

velocity will be obtained and the immediate spread or flare of the discharged gas prevented without, however, providing any restriction or interference to the gas flow, whether regulated for a minimum or a maximum discharge, with the result that the momentum and efficiency of the discharging gas 30 is not destroyed; while adjustment to meet the variations in gas pressures may be easily and readily made by the user without in any way interfering with the connections or assembly of the respective parts of the burner. 35 40

What I claim is:—

A gas regulating device comprising a cylindrical member of equal diameter throughout and provided with a uniform bore terminating adjacent to one end whereby relatively thick side walls and one end wall are provided, a minute central opening in said end wall communicating with the bore and of smaller diameter than the diameter of the bore, said end of the member being provided with an external bevel of length less than the thickness of said end wall, the member being provided with slits radiating from the bore and said minute opening. 45 50

GUSTAVE F. SCHMIDT.
